UNITED STATES PATENT OFFICE.

JOHN L. JONES, OF TORONTO, ONTARIO, CANADA, ASSIGNOR TO DOMINION PAPER BOX COMPANY, LIMITED, OF TORONTO, ONTARIO, CANADA.

PAPER BOX.

1,141,343.

Specification of Letters Patent. Patented June 1, 1915.

Application filed August 4, 1914. Serial No. 855,002.

To all whom it may concern:

Be it known that I, JOHN L. JONES, of the city of Toronto, in the Province of Ontario, Canada, a subject of the King of Great Britain, have made certain new and useful Improvements in Paper Boxes, of which the following is a specification.

This invention relates to paper boxes of the type in which ends and sides are turned up and the corner pieces connecting them folded and laid against the ends, and interlocked with infolded flaps or tongues on the ends, and my object is to devise means for locking the ends to the corner pieces which will enable me to reduce the depth of the end flaps to a minimum and thus effect a considerable saving in stock over the boxes now commonly employed which demand end flaps or tongues of considerable depth. (For example the "Birley" box patented in the U. S. Mar. 19th, 1895, No. 536,064.)

I attain my object by means of the constructions hereinafter specifically described and illustrated in the accompanying drawings in which—

Figure 1 is a plan view of the blank of which the box is formed; Fig. 2 a plan view showing the box partly set up; and Fig. 3 a perspective detail of one corner of the box as set up.

In the drawings like numerals of reference indicate corresponding parts of the different figures.

The blank shown in Fig. 1 comprises an integral sheet of suitable material suitably cut out and scored to form the following connected parts,—the bottom 1, the walls 2, the corner pieces 3 connecting the walls, a pair of locking tongues 4 on opposite end walls, a pair of locking tongues 5 adjacent the tongues 4, and the end flaps 6 cut with their ends extending over the locking tongues 5.

Score lines 7 are formed between the bottom and the walls. Extensions of these score lines form the score lines 8 between the walls and corner pieces. Diagonal score lines 9 are formed extending from the inner to the outer corners of the corner pieces 3. The inner edges of the locking tongues 4 are substantially perpendicular to the edges of the walls.

As a simple cut forms the division between the tongues 4 and 5 the outer edges

of the tongues 5 are necessarily also substantially perpendicular to the edges of the walls.

The locking tongues 5 are separated from the flaps 6 by the cuts 10. The parts of these cuts 10 adjacent the walls 2 are so positioned that when the parts of the box are folded as shown in Fig. 2 the diagonal edges of the tongues 5 may, by the infolding of the locking tongues, be brought into substantial co-incident with the diagonal score lines 9.

Before the outer sides of the flaps 6 are reached the cuts 10 are preferably laterally directed to intersect the lines of division between the tongues 4 and 5. The flaps 6 are thus given a rough T shape.

The blanks may be shipped in the form shown in Fig. 1 but I deem it preferable to partly set them up as shown in Fig. 2 before they are shipped.

It will be noted that the flaps 6 are folded inward and that the side walls are folded in so that the corner pieces overlie the ends of the flaps 6. The locking tongues 5 are folded over the corner pieces and are preferably secured thereto by staples or paper fasteners as indicated.

When the box is to be set up the end walls are turned up at right angles to the bottom, the corner pieces folding along the diagonal score lines 9 as indicated in Fig. 3. The locking tongues 4 are then turned down inwardly and engaged with slots 11 formed in the corner pieces in suitable position as shown. The box will now be found to be perfectly locked so as to retain its shape during use. In a wide box it may be preferable to cut a tongue 12 in each end wall for engagement by the flaps 6 as shown.

The tongues 4 having their inner or locking edges substantially perpendicular to the edges of the end walls effectively resist any side pull caused by outward pressure on the side walls of the box. The tongues 5 hold the points of the folded corner pieces closely against the end walls while the folded in flaps 6 stiffen the ends and give a finished rounded edge to the middle portions of the end walls.

The locking tongues 5 and the flaps 6 are not essential to the locking if the corner pieces be stapled to end walls as shown in Fig. 2, but they are preferably em-

ployed as no material will be saved by omitting them and as a better finished end is obtained by their use.

From the above description it will be seen that I have devised a paper box in which the locking is accomplished with a minimum of material extending in the blank beyond the edges of the end walls, and this saving of material results in marked economy in the 10 cost of manufacture.

What I claim as my invention is:

1. A paper box formed from an integral sheet of material consisting of a bottom, four walls, corner pieces folded diagonally 15 and turned in against opposite walls; a pair of locking tongues on each of said opposed walls having their inner sides substantially

20 perpendicular to the bottom, the inner sides of the corner pieces being provided with slots to receive the tongues; a pair of locking tongues on each of said opposed walls between the aforesaid tongues fitting within the folded corner pieces and substantially contacting with the angle of the fold.

25 2. A paper box formed from an integral sheet of material consisting of a bottom, four walls, corner pieces folded diagonally and turned in against opposite walls; a pair of locking tongues on each of said opposed 30 walls having their inner sides substantially perpendicular to the bottom, the inner sides of the corner pieces being provided with slots to receive the tongues; a pair of locking tongues on each of said opposed walls 35 between the aforesaid tongues fitting within the folded corner pieces and substantially contacting with the angle of the fold; and fastening means securing the last mentioned tongues, the corner pieces and walls to- 40 gether.

3. A paper box formed from an integral sheet of material consisting of a bottom, four walls, corner pieces folded diagonally and turned in against opposite walls; a pair 45 of locking tongues on each of said opposed walls having their inner sides substantially

perpendicular to the bottom, the inner sides of the corner pieces being provided with slots to receive the tongues; a pair of locking tongues on each of said opposed walls between the aforesaid tongues fitting within the folded corner pieces and substantially contacting with the angle of the fold; and flaps on said walls turned in and having their ends shaped to tuck under the corner 55 pieces.

4. A paper box formed from an integral sheet of material consisting of a bottom, four walls, corner pieces folded diagonally and turned in against opposite walls; a pair 60 of locking tongues on each of said opposed walls having their inner sides substantially perpendicular to the bottom, the inner sides of the corner pieces being provided with slots to receive the tongues; and infolded 65 parts on the said walls between the tongues suitably engaged both under and in the folds of the corner pieces to retain said parts in their infolded position and stiffening the end walls of the box.

5. A blank for a paper box comprising an integral sheet of material scored and cut to form a bottom; four side walls; corner pieces connecting the walls adapted to fold diagonally and provided with slots; and end 70 flaps on opposite walls each cut to form two tongues with their inner sides substantially perpendicular to the edge of the wall, a pair of tongues with their outer sides against the adjacent sides of the first mentioned 75 tongues, and a central part or flap having its ends extended over the second mentioned tongues, the slots in the corner pieces being so placed that the first mentioned tongues may be engaged therein when the box is 80 set up.

Toronto this 29th day of July A. D. 1914.

JOHN L. JONES.

In the presence of—

J. EDW. MAYBEE,
GEORGE P. MACKIE.
